UNITED STATES PATENT OFFICE.

JAMES B. HAMMOND, OF NEW YORK, N. Y.

TYPE-WRITING MACHINE.

SPECIFICATION forming part of Letters Patent No. 290,420, dated December 18, 1883.

Application filed October 19, 1883. (No model)

To all whom it may concern:

Be it known that I, JAMES B. HAMMOND, a citizen of the United States, residing in the city, county, and State of New York, have invented a new and useful Improvement in Type-Writing Machines, of which the following is a specification.

My invention relates to that class of type-writing machines for which several Letters 10 Patent have heretofore been issued to me, of which Nos. 232,402, 249,930, and 253,475 may be particularly referred to; and the object of my improvement is to avoid the difficulties and complications of mechanism incident to a 15 machine in which the type-wheel moves in either direction from a normal position. I attain this object by the mechanism illustrated in the accompanying drawings, in which—

Figure 1 is a vertical sectional and Fig. 2 20 plan view.

Only so much of the mechanism of a type-writing machine is shown in the drawings as is necessary to a full understanding of my invention.

25 The key-levers B are fulcrumed on knife-edged rib A, and operate to elevate the stoppins O, guided by the stationary plate D.

On the frame of the machine are mounted two driving-levers, as G, having horizontal 30 and vertical driving-arms. They are mounted on shaft H in the manner shown, to secure a rigid bearing. Their horizontal arms are so disposed over the key-levers that a varying amount of movement is imparted to said arms, 35 which increases as the distance of the operated key-lever from the fulcrum of said driving-levers decreases—the greater the movement of the driving-lever the greater of course the movement of the type-segment.

40 F represents a guard-plate; N, a shouldered shaft passing through frame R, capable of being elevated by mechanism (not shown) and depressed by a spring, m, whose lower end presses against a collar (not shown) on the shaft.

I represents the paper-carriage guide-rod.

N represents the type-segment shaft, and M means for holding the type-segments thereon.

50 No part of the mechanism so far referred to

is claimed in this application, as the same is embraced in an application filed on the 20th day of September, 1883.

On the segment-shaft are mounted two type-segments, k and l, each carrying a portion of 55 the total number of characters required. The arrangement of characters preferred is to confine lower-case letters or small capitals to the upper horizontal row of each type-segment, large capitals to the second horizontal row, and 60 figures and punctuation-marks to the lower row, adding also to the upper and middle rows such few punctuation-marks as are of frequent occurrence. The type-faces of these two type-segments are disposed as shown in Fig. 1, and 65 each, when operated, is brought into proper position opposite the impression-hammer. When the segment-shaft is elevated, both rise together and equally to bring the second or 70 third line or row of type thereon into alignment with the impression-hammer. (Not shown.) Type-segment k is provided with a sleeve, a, which is mounted on the shaft N, and abuts against the shoulder on the same. Type-segment l is provided with a like but 75 larger sleeve, b, which surrounds the sleeve a of segment k, and also abuts against the shoulder on the shaft. The upper end of sleeve b also abuts against a shoulder on sleeve a, to 80 prevent vertical displacement. The nut M, which screws onto the diminished end of shaft N, holds the type-segments against vertical displacement.

Secured to each type-segment is a depending connecting-pin, e, which slides through an 85 opening in a link, f, whose opposite end is pivoted by means of a screw, g, or any other suitable means, to an ear on the vertical arm of driving-lever G. Each type-segment has its own pin, link, and driving-lever, and either 90 one can, therefore, be operated and returned to normal position without moving or disturbing the other or its driving mechanism. Each driving-lever is returned to operative position by a spring, (not shown,) and being positively 95 connected with its type-segment, returns the latter also to normal position. Two stop-arms, r and s, are provided, the former having a sleeve, c, and the latter a sleeve, d, the latter surrounding the former and the former sur. 100

rounding type-segment sleeve *b*. The lower ends of both sleeves *c* and *d* rest on frame *R*, and the outer sleeve, *d*, is provided with a flange or rib, which fits the groove of a roller, 5 *E*, secured to plate *R*, and prevents vertical displacement. Sleeve *c* may be guarded against displacement by a suitable connection with sleeve *d*. Each stop-arm sleeve is provided with a lug or projection, *t*, for co-operation 10 with the pins *e* of the two type-segments. These lugs are placed a definite distance from the stop-arms, and for this distance the pins *e* can move without moving the stop-arms, the purpose of which arrangement will be present- 15 ly explained.

It will be observed that the pin *e* upon the return of the segment will come in contact with the stop-arm of that segment, and cause it to return to its normal position; but for the purpose of securing independent, and therefore more rapid, movement of the stop-arm, I prefer to provide each stop-arm with a light returning-spring, whereby it may be returned to its normal or starting position before the pin 25 *e* has reached it. A central pin, *2*, arrests both stop-arms at this normal or starting position.

The normal position of the type-segments is represented by type-segment *k* in Fig. 2. The 30 distance of the forward end of each segment from the impression-point is equal to the circumferential length of the type-face, and this space is required in order that each type-segment may oscillate to the full extent of its movement without interference with the other; or, in other words, the normal position of each type-segment is outside the field of oscillation 35 of the other. The extent of this field is about equal to twice the circumferential length of 40 the type-segment face.

As each type-segment has to oscillate a distance substantially equal to its circumferential length before the letter nearest the impression-point is in position to effect an impression, it is evident that space is provided for 45 the application of inking-rollers, past which the segments may oscillate to receive ink before reaching their printing position; but this feature or combination, involving inking-rollers, is not claimed herein, as it will form the 50 subject of a future application.

The operation of the mechanism described is as follows: Depression of a right-hand key-lever tilts the right-hand driving-lever, whose 55 vertical driving-arm, moving to the rear, oscillates, through pin *g* and link *f*, the right-hand type-segment, moving it to the left from its normal position. When the type-segment has been moved a distance equal about to its circumferential length, its pin *e* strikes the lug 60 of the right-hand stop-arm, *s*, and for the remainder of the forward movement type-segment and stop-arm move together until the stop-arm arrests the type-segment by reason 65 of its contact with the proper stop-pin. When the key-lever is released, the spring, before de-

scribed as arranged to operate on driving-lever *G*, returns the type-segment *l* to its normal position, and a spring also returns the said stop-arm to its normal position. During 70 this oscillation and operation of the right-hand type-segment and driving mechanism the left-hand type-segment and its driving mechanism have been at rest. When a left-hand key-lever is operated, the left-hand type-segment is 75 oscillated, in the same manner as before described with regard to the right-hand type-segment.

By reason of the extent of movement permitted to pin *e* between the stop-arm and its lug before it comes in contact with either, the considerable advantage is secured that the key-lever which has moved the type-segment need only be returned half-way to position before another key-lever operating the same type-segment can be depressed, which permits freedom of movement in the fingering, and avoids the necessity of returning each key-lever to position before the next one pertaining to the same segment is touched. The construction 90 also gives the same flexibility and freedom of movement in the use of keys on opposite sides.

Another advantage is that a convenient space is secured for the location of inking-rollers, thus permitting an inking-ribbon to be 95 dispensed with.

What I claim, and desire to secure by Letters Patent, is—

1. The combination, with two type-segments, each carrying a portion of the total number of 100 characters desired and both arranged in the same plane, of a series of key-levers and two intermediate driving mechanisms independent of each other, all substantially as described.

2. The combination, with two type-segments, 105 each carrying a portion of the total number of characters desired and mounted on the same shaft with the two type-faces arranged in the same circumferential line, of a series of key-levers and two separate intermediate driving 110 mechanisms, all substantially as described.

3. The combination, with two type-segments, each carrying a portion of the total number of 115 characters desired and mounted on the same shaft with the two type-faces arranged in the same circumferential line, of a series of key-levers, and a separate intermediate driving mechanism for each type-segment positively connected thereto, all substantially as described.

4. The combination, with two independent 120 type-segments mounted on the same shaft and supplementary to each other, as described, of two independent stop-arms, two independent driving mechanisms, and a series of key-levers, all substantially as described.

5. The combination, with two independent 125 type-segments supplementary to each other, as described, mounted on the same shaft and lying in the same circumferential line, of a series of key-levers and two separate intermediate driving means for independently oscillating each type-segment in one direction only 130

from a normal position, all substantially as described.

6. The combination, with two type-segments supplementary to each other, as described, placed in the same plane and removed, when in their normal position, the distance, substantially, of their circumferential length from the impression-point, of two independent driving mechanisms and a series of key-levers for operating the same, all substantially as described.

7. A type-segment arranged in its normal position at a distance equivalent to its circumferential length from the impression-point, a stop-arm provided with a lug located relatively as described, and a pin or projection connected with the type-segment which has free movement for a certain distance between stop-arm and lug, and operates to move forward and return the stop-arm, in combination with key-levers and intermediate means for moving said type-segment, all substantially as described.

8. The combination, with a type-segment, of a series of key-levers and intermediate driving mechanism consisting of a lever operated by the key-levers, a pin or projection on the type-wheel, and a link connected at its opposite ends to said lever and pin, substantially as described.

9. The combination, with two type-segments supplementary to each other, as described, each provided with a sleeve, one fitting over the other and mounted on a shouldered shaft, of two stop-arms, also provided with sleeves fitting over each other and over the outer sleeve of the type-segments.

10. The combination, with a shouldered shaft, of two type-segments supplementary to each other, as described, and arranged in the same horizontal plane, each provided with a sleeve, one fitting over the other, and the inner sleeve fitted to said shaft.

11. The combination, with a type-segment provided with a depending pin, of a series of key-levers, a driving-lever, and a link provided with an opening through which the type-segment pin may freely slide for the purpose of permitting the type-segment to be elevated without disturbing its connection with the driving mechanism.

In testimony whereof I have signed my name to this specification in the presence of two subscribing witnesses.
